United States Patent Office

Des. 231,911

Patented June 25, 1974

231,911

NOVELTY CART

Joseph M. Baker, 438 S. Elm Drive,
Beverly Hills, Calif. 90212

Filed July 21, 1972, Ser. No. 274,003

Term of patent 7 years

Int. Cl. D12—08

U.S. Cl. D12—1

Fig. 1

Fig. 2

Fig. 3

Fig. 4

Fig. 5

FIG. 1 is a front perspective view of a novelty cart, showing my new design;

FIG. 2 is a rear elevational view thereof on an enlarged scale;

FIG. 3 is a front elevational view thereof on an enlarged scale;

FIG. 4 is a top plan view thereof on an enlarged scale;

FIG. 5 is a right side elevational view thereof on an enlarged scale.

I claim:

The ornamental design for a novelty cart, as shown and described.
